[57] CLAIM

The ornamental design for a file for photographic slides, as shown and described.

DESCRIPTION

FIG. 1 is a perspective view of a file for photographic slides showing our new design;

FIG. 2 is a left side elevational view thereof;

FIG. 3 is a right side elevational view thereof;

FIG. 4 is a top plan view thereof; and

FIG. 5 is a bottom plan view thereof.

The broken lines shown in FIG. 1 represent a design pattern which forms a part of the claimed design.
